UNITED STATES PATENT OFFICE.

RALPH H. UPSON, OF BIRMINGHAM, MICHIGAN.

BALLOON.

Application filed May 18, 1923. Serial No. 639,739.

To all whom it may concern:

Be it known that I, RALPH H. UPSON, a citizen of the United States, residing in the village of Birmingham, county of Oakland, 5 State of Michigan, have invented certain new and useful Improvements in Balloons, of which the following is a specification, reference being had to the accompanying drawings, illustrative of one particular embodiment of my invention.

This invention relates to balloons, and more particularly to features of construction applicable primarily to the so-called spherical balloon as a lighter-than-air craft 15 for the general uses of balloons.

The particular objects are to provide a balloon more efficient in service than those heretofore made. Among the particular objects are to provide a construction which 20 will make possible a higher ceiling or range of altitude, increase the stability, that is improve the ability to maintain a more constant altitude, to reduce the radiation effect, improve the ability to shed rain or snow, in- 25 crease the efficiency of manipulation, reduce the amount of ballast supply necessary for a given journey or for any long distance flights, and generally to improve the characteristics and thereby the performance of 30 balloons in actual service.

The inventions will be more specifically set forth with relation to a specific embodiment of a balloon illustrated in the accompanying drawings and described in detail 35 hereinafter, and in respect to which the general characteristics will be first referred to.

The envelope of the balloon constitutes a 40 large element of weight, but heretofore the material of the envelope if used without a net, involved stiffness against shock and irregular strains. By using the fabric with a single bias ply, with the warp in adjacent gores slanting in opposite directions oblique 45 to the seam between the gores, all necessary strength and flexibility is provided without any net. Thus with a single ply with panels of fabrics on the bias considerable weight is saved and at one stroke, with ample shock 50 resisting qualities and with the force distributing properties peculiar to a net.

With this construction stress resisting tapes are secured to the seams between the 55 gores on the upper part of the balloon, each tape being connected to a foot rope. The general construction permits the use of a

reduced number of foot ropes compared to present types of balloons and still admirably resisting all stresses in flight. To resist the irregular stresses during inflation a so-called 60 "catenary band" is attached on a circle connecting the lower ends of all the tapes, and the upper ends of all the foot ropes.

At the top a proper construction to shed 65 snow and otherwise meet the conditions at the apex of the balloon, is obtained by making the top double ply of conical shape, and arranging for interior manipulation so that the pilot may readily throw off any chance 70 accumulation of snow.

In the preferred form the envelope comprises a white outer surface such as bleached cloth with a white rubber backing which provides an improved screen against radiation. This indirectly effects a saving of a 75 substantial amount of ballast which otherwise would be required for the same flight performance.

A most visible change resides in the providing of a flounce or annular fabric rim 80 projecting substantially from the equator of the envelope and which I call the equatorial rim. This rim is so arranged that it provides a generally horizontal area having a dampening effect on vertical motion. 85 While this may be variously arranged and constructed, in the preferred form it comprises fabric secured to the envelope completely around the periphery at or close to the equator, and held in a general radial 90 direction by struts secured below its line of attachment and extending radially outward and upward to the edge of the equatorial band and there secured to a rope which is fastened radially in the equatorial 95 band with its ends secured at the envelope to or adjacent the stress tape, and with the other or free end running down and leading to the load ring above the basket in a position capable of manipulation by the pilot. 100 This equatorial band and its struts are folded upward when the balloon is being inflated, and are readily secured in a temporary manner in the upward furled position, but by arrangement which permits the 105 pilot to voluntarily pull down the equatorial band from its furled position and thereby "set" it in operative position so soon as desired after the flight has commenced.

Thereafter the equatorial band ropes carry 110 any strain on the underside of the equatorial band which may result from a drop of the

balloon, while a rapid rise of the balloon throwing a strain on the upper side of the equatorial band is resisted by the character of construction and its struts held in position by the rim ropes.

This equatorial band or rim is so shaped that it will shed rain, and any snow sliding on to it may be readily shaken off by manipulation of the rim ropes. By this construction moisture is shed clear of the lower half of the envelope, thereby keeping the lower half of the balloon dry with the resultant great minimizing of moisture absorption. This, as another item, eliminates a call for ballast that would otherwise be necessary, and assures general lightness, or in turn a greater flight capacity both as to ceiling and duration in air.

The general dimensions of this equatorial rim are preferably approximately as shown in the example herein referred to which are the results of careful tests.

The arrangement of catenary band with stress tapes includes features permitting hold-down ropes during inflation entirely separate from the regular foot ropes, thereby permitting the handling during inflation of the lower half, by separate ropes, saving wear and tear on the foot ropes proper and keeping the sand bags attached to the inflation ropes entirely clear of the congested space where the basket is moved into position for connection with the load ring. In case of high wind the inflation ropes can be kept reeved until the last moment and can serve as hold-down ropes eliminating the necessity of using sand bags around the ropes attached to the lead ring and avoiding the chance of sand bags going out of reach, as well as avoiding the crush of men and sand bags around the vicinity of the basket at just the time when they should be clear for proper control and manipulation by the pilot.

In this particular embodiment of my invention, the inflation of the top half of the balloon is handled by means of a separate "inflation net" which is pulled off after transferring the sand bags to the hold-down ropes.

In order that the pilot may reach land even though dropping on water, suitable pneumatic pontoons of inflated fabric are provided under the basket, thereby relieving the weight of the basket when it touches the surface of any water and permitting the maximum chance of sailing without danger of immersion of equipment, over the surface of the water to adjacent land without outside assistance.

These pontoons are connected with each other to form a single unit, detachable from the basket, and may be used as a separate life boat or raft in case of emergency.

As usual the mixing of air with the gas

must be avoided, and the advantage of the old-fashioned appendix is accomplished in a changed form involving a light inner sleeve at the bottom, while a semi-automatic appendix closing device may be used in addition.

With these principal characteristics and their relative importance indicated they will now be more fully appreciated with reference to the detailed description involving an example of the practice of my invention.

A particular embodiment of my invention is shown in the accompanying drawings, in which:

Fig. 1 is an elevation of balloon as suspended in air.

Fig. 2 is an elevation of the balloon with top half inflated, with dotted position shown with further progressive inflation.

Fig. 3 is a side elevation on a larger scale, illustrating parts in more detail.

Fig. 4 is top plan of Fig. 3.

Fig. 5 is a vertical section of Fig. 3 on line 5—5.

Fig. 6 is a vertical section on an enlarged scale, part fragmentary, of the cone and suspension tape connections.

Fig. 7 is a fragmentary view showing on a larger scale details of catenary band.

Fig. 8 is a vertical section, fragmentary of the equatorial band and its connections to the envelope.

Fig. 9 is a fragmentary view showing vertical section connection of the equatorial band to the envelope.

Fig. 10 is a fragmentary perspective showing the connection of the equatorial rim struts.

The balloon comprises the generally spherical envelope including the top half 1 and the lower half 2, a cone 3 forming the apex, suspension tapes 4, the equatorial rim 5, catenary band 6, foot ropes 7, load ring 8 and basket 9.

In the particular embodiment herein shown, the envelope comprises in the upper half a plurality of gores 10—10 made up of panels of single ply fabric set on the bias, so that the warp of the panels 11 in adjacent gores is at an angle, as shown in Fig. 4.

The cone 3, however, is made of double ply fabric, and close to the bottom adjacent the appendix, the envelope is strengthened by being made of two-ply, and two-ply is used in the suspension bands. A single ply fabric laid on the bias, in combination with the other features of construction, involves the various advantages which will be hereinafter more particularly set forth.

The double ply cone has secured near its edge the top end of a plurality of suspension tapes 4 which may be sewed to the fabric and covered with a regular patch. As these suspension tapes pass along the meridians of

the top half of the envelope, they are readily secured to the envelope as they consist of flat strips of rubberized silk tape and are reinforced by additional plies of tape progressively, each additional ply beginning at a further distance from the cone as at 4^a, 4^b, 4^c, 4^d. These suspension tapes are covered with a strip of bias tape, thereby protecting and securing the suspension tapes to the envelope. At the lower end of the suspension tapes they pass into the catenary band 6, as shown in detail in Fig. 7, so that the lower end where the lift strain of the balloon is carried, the end of the suspension tape is in position to be connected with the catenary ropes 12 joining at a thimble 13 at the upper end of the foot ropes 7. At this junction a thimble 14 is spliced in order to form a permanent connection permitting the reeving of separate inflation lines or hold-down ropes at this point in order to permit the handling during inflation by separate lines around the balloon, without interference with the manipulation of the foot ropes during the preparation for flight.

The catenary band 6 involves a double ply of material secured to the envelope below the equatorial rim, and the lower edge of the catenary band has grummet ropes bound in which transmit the strain from the foot ropes to the best advantage for distributing irregular angular pulls such as occur during inflation.

Just above the catenary band, what I call an equatorial rim is provided for great advantages of operation which will be described in more detail hereinafter. This equatorial rim comprises fabric section 15 secured to the envelope around the equator, 40 being cemented thereto to form a watertight joint. At intervals, preferably corresponding with and at each suspension tape meridian, a rope 16 is fastened to the envelope by having its end frayed as at 16^a, and cemented and covered with a suitable waterproof patch. The rope passes through a pocket on the underside of the rim fabric 15, the fabric being stretched as the rope is secured to it and a bias tape then cemented 45 over the rope to suitably unite it with the fabric of the rim and properly distribute the rope strains throughout the fabric. Near the edge of the rim, a rope end is spliced to the main rope 16 in order to tie the rope to the end 17^a of the strut 17 which is secured 50 at its other end 17^b by a lash line to the rope-eyes 18, 18 forming a strut-hinge 19 secured to the envelope. This strut-hinge 19 is formed by fraying the ends of the rope-eyes 55 spreading and cementing them and covering them by suitable patches to the surface of the envelope. Thus the rim strut 17 can fold upward against the envelope, and preliminary to a flight and during the course 60 of inflation of the balloon these rim struts

are folded up, thereby folding up the rim itself, and are held temporarily in the upturned position by a light breakable line or lashing 20 secured to an eye 21 fastened to the outer surface of the envelope. The line 70 16 continues free at the outer edge of the rim fabric and extends downward to the load ring 8, so that after the balloon has started on its flight the pilot can pull the line 16, thereby breaking the temporary tie 20, 75 whereupon the rim struts 17 spread out and form a radial strut to support the rim fabric or equatorial flounce, which is then held in the extended position for the rest of the balloon flight, with the ropes 16 having their 80 lower end accessible to the occupants, serving to stiffly hold the equatorial rim against any upward relative air current.

The control lines include the valve line 22 serving to actuate the valve 23. This line 85 passes through the sleeve 24 at the bottom of the balloon permitting suitable connections for operation without interfering with the gas-tightness of the envelope. Line 25 passes from proximity to the basket through 90 the similar sleeve 26 and through the balloon to the underside of the cone where it is attached to the rip panel 27 provided for the usual emergency opening. A snow line 28 extends through the appendix 29 95 through the middle of the balloon to the underside of the cone or top cap 3, and this snow line preferably has a crow's-foot upper end spreading to a plurality of points around the centre of the cone and attached 100 at the inner side so that any strain on the snow line will pull the double ply cap down without distorting its apex. In this manner the snow line serves to pull down and release the cone in order to jar and loosen any 105 accumulation of snow and cause it to be shed over the sides of the upper half of the envelope.

The basket 9 is attached with the usual basket ropes to the load ring 8, and the usual toggles are provided on the ropes extending just above the load ring for ready attachment to the eyes in the lower ends of the foot rope 7. Below the basket inflatable raft 30 may be provided which, while being made of 110 light material is of sufficient buoyancy to provide floating capacity on water of the basket and occupants.

At the lower end of the appendix 29, a relatively light weight inner sleeve 31 forms 115 the check valve against air, and a semi-automatic appendix closing device may be also added, consisting of an outside elastic cord which contracts the appendix sleeve around a cylindrical cushion 32 attached to the snow 120 line.

It will be noted that the old fashioned net which formerly served to enclose the upper half of the envelope and carry the strains, is entirely eliminated so far as actual flight is 130

concerned. On the other hand, all of the strains involved are admirably resisted by the envelope made with the different gores having panels with the fabric warp on the bias, and at the junction of the adjacent gores the suspension tapes running from the cap down to the catenary band, provide the necessary strength increasing with the distance from the apex and which becomes a maximum at the lower end where connection is made with the foot ropes. The alternate bias direction of the warp of the fabric of the panels produces the advantageous results, and with the combination of elements only a single ply of fabric is required for the necessary strength throughout the main portion of the envelope. Plain bleached cloth is found very effective with a white rubber backing. This in itself effects a substantial saving in weight as compared with material previously used.

The equatorial rim involves marked advantages. It provides means for completely shedding any water which runs down the top half of the envelope, and sheds snow as well. This laterally projecting flounce or equatorial rim also has a dampening effect on the vertical movement of the balloon, so that with a sudden tendency to rise the pressure on the top of the equatorial rim is resisted by the rope and strut structure, and when a sudden tendency to fall develops, the equatorial rim ropes 16 being fastened to the load ring resist the upward stress on the equatorial rim.

With the shedding of any rain or condensation or snow over the periphery of the equatorial rim, it will be seen that the entire lower half of the envelope is protected and remains dry. Thus with the prevention of moisture contacting with the lower half of the envelope, there is a great saving in operation compared with balloons heretofore, which during a rain increase their weight materially due to the absorption of moisture.

With the cone or apex construction, any accumulation of snow can be shaken off and when sliding down the envelope will be deflected by the inclination of the equatorial rim, and if not completely shed, then the rim guy ropes can be pulled to shake the fabric of the equatorial rim and thus assure shedding of the snow and prevent in the greatest possible degree any encumbrance of load due to snow or water.

Thus in the starting of flight with a balloon, as well as in the maneuvering of the balloon, it will be appreciated that the inventions herein described have marked advantages. During inflation the upper half may be inflated, and the stress tapes resisting the lift are held down by land ropes passing through the thimbles 14, and these ropes may be held down by men disposed around the balloon, and with sand bags attached if de-

sired, keeping both men and sand bags well away from the position where the basket is to be attached. The foot ropes 7 at the same time remain free until the balloon is sufficiently inflated and allowed to rise to the extent where the basket is put in place, and the foot ropes then dangling free are led to their toggles above the load ring and are readily attached without any hold-down strain, because the ropes passing through the thimbles 14 are at that time serving the purpose of control. As soon as desired the hold-down ropes are pulled free of the thimbles and the balloon is ready for release.

The balloon may be inflated with the equatorial rim furled up and therefore not interfering with the get away, and the equatorial rim may remain furled until any desired altitude is reached and until its functions are desired by the pilot. At the desired time the rim ropes are pulled, thereby setting the equatorial rim in place with the struts holding it out and the ropes of the rim forming the upper tie or tension member for radially outward strain.

During flight the advantages heretofore mentioned of shedding snow and rain will now be fully understood, and it will be seen that any vertical up or down movement will be damped by the horizontal annular area of the equatorial rim. At any time, if desired, the rim hold-down ropes can be relieved to make the drop of the balloon free, and the rim can be shaken to clear it of moisture and snow by these ropes with their lower ends accessible to the occupants. The fabric in the rim is so arranged as to take the necessary strain, with the warp tangential, and between props or struts the edge may be left free of treatment such as paraffining, and may be perforated to assure the maximum shedding of water in any scallop formed between the props,—as shown in Fig. 4. The snow line running from the inner surface of the cone apex down to the basket may have a rubber section, shown at 33, Fig. 6, in tension, so as to accommodate the usual stretch involved in variation of expansion of the envelope.

The rim may have other struts, such as may be embodied in the material instead of ropes, and a stiffer construction provided, which, however, is thought to be inferior to the construction as herein particularly shown and described. Instead of a breakable line at 20 an elastic cord can be used which will pull the rim back to its upper or folded position again at any time the lines 16 are released.

Wherever the words "spherical balloon" are used in these specifications and claims, they are to be understood as not limited to balloons of geometrical sphericity, but as including balloons of any spheroidal or approximately spherical shape.

While various modifications may be made without departing from the spirit of my invention, what I claim and desire to secure by Letters Patent is:

5. 1. In a balloon, an envelope, an annular band of pliable material secured substantially at the equator of the envelope, and means to hold said band extended in a substantially horizontal position radially outward from the envelope.
10. 2. In combination in a balloon, an annular equatorial band secured at its inner periphery to the envelope, a plurality of struts attached to the envelope at one end and to the outer periphery of said band whereby the latter is held in a generally horizontal position.
15. 3. A balloon having an equatorial band, means to hold said band in a substantially horizontal extended position.
20. 4. A balloon having an equatorial band with one edge secured to the envelope of the balloon, struts projecting from the envelope to the band, and lines extending from the outer periphery of the band to lower connections on the balloon.
25. 5. In combination in a balloon, an annular band secured at one edge substantially at the equator of the balloon envelope, a plurality of struts secured to the envelope below the line of attachment of the band and extending to a connection adjacent the outer periphery of the band.
30. 6. An equatorial band construction for spherical balloons, comprising in combination with a balloon envelope an annular band, means to attach the inner periphery of the band to the envelope, a plurality of ropes secured in a radial position on the band and having their ends secured to the envelope, struts registering with every rope and having one end secured to the envelope and connected at their outer end to the rope between its point of attachment to the envelope and the free dependent end of the rope.
35. 7. An equatorial band construction for spherical balloons, comprising in combination with a balloon envelope an annular band, means to attach the inner periphery of the band to the envelope, a plurality of ropes secured in a radial position on the band, an inclined strut engaging each rope at or near the outside edge of the band, an articulated means to secure the inner end of the strut to the envelope.
40. 8. A spherical balloon having an envelope, a supplementary radially projecting annular band of material attached substantially at the equator of the envelope, a plurality of struts hinged to the envelope, a plurality of ropes attached to the envelope and extending to the outer periphery of the band and each secured to the outer end of a strut,
45. and a continuous length of rope extending downward therefrom to a point accessible to the occupants of the balloon.
9. A spherical balloon equatorial band including a plurality of ropes having their ends secured to the envelope, a strut for each rope secured to the envelope below the rope end attachment, a connection between strut and rope, and means for securing the equatorial band to extend intermediate the ropes around the balloon.
10. A spherical balloon envelope comprising a plurality of gores throughout the upper half of the lift section, diagonal panels of material forming each gore and tapes covering the seams between gores.
11. A spherical balloon envelope, having a plurality of substantially inextensible meridian stress tapes or cords from near the top down the sides of the upper half, diagonal panels of fabric forming the intervening gores, and the sole intervening connection disposed whereby the fabric is secured on the bias to the meridian stress members with the two gores on each side of each member having their warp oppositely oblique to the longitudinal direction of the stress members.
12. A spherical balloon envelope comprising a plurality of gores forming the top half and made of single ply fabric laid on the bias throughout with respect to the meridian lines with the warp oppositely oblique in adjacent gores, and having the junction of adjacent gores secured to meridian stressed tapes.
13. A spherical balloon envelope comprising fabric laid throughout on the bias with respect to each gore, and having the warp of fabric oblique to the seams between gores and oppositely positioned in an oblique direction on adjacent gores and having meridian stressed tape secured at the junction of the adjacent gores.
14. A spherical balloon envelope, comprising single-ply fabric, meridian stressed tapes from near the top to the equator, with the warp of the fabric in each gore oppositely oblique to the intervening stress tape and secured thereto, thereby providing substantially inextensible flexible meridian members with intervening bias panels to resist the expansive pressure of the balloon.
15. In a spherical balloon, an apex shedding-cone formed of multiple ply fabric and the major extent of the top section of the envelope formed of a lesser ply fabric.
16. A balloon having a cone forming the apex and made of multiply fabric, the adjacent envelope extending to the equator formed of lesser plies of fabric, a catenary band at or below the equator having its lower rim reinforced.
17. An envelope for a spherical balloon

consisting of panels of single ply fabric on the bias throughout the lift section, an apex cone of multiple ply fabric.

18. A spherical balloon envelope consisting mainly of single ply fabric comprising a plurality of meridian stress members secured to the envelope extending from near the apex to the equator.

19. A spherical balloon envelope, consisting mainly of single-ply fabric, a plurality of meridian-stress members secured to and having the fabric as their sole interconnection, each meridian member formed of material of increasing strength from top to bottom.

20. A spherical balloon envelope, consisting throughout the major portion of the lift section of fabric having its warp in an oblique direction, and formed and interconnected in a plurality of gores, a plurality of meridian stress members consolidated with the outer surface of the fabric at the seams of the gores.

21. A spherical balloon having an apex cone formed of a greater number of ply than the adjacent lift section of the envelope, meridian stress tapes extending from the cone to the equator and secured throughout their length to the fabric of the envelope.

22. In a balloon, a single ply envelope, a cone of heavier construction, stress members secured to meridian elements of the top half of the envelope, a catenary band, means for attachment of foot ropes at the junction of the stress members and the lower rim of the catenary band.

23. In a balloon, a single ply envelope, a cone of heavier construction, a catenary band below the equator, stress members extending from the cone throughout a plurality of meridian lines and secured to the envelope above the equator and having free lower ends joining with the stress member of a catenary band, eyes or like means close to the foot rope attached at the junction of the meridian stress members and catenary stress members for separable connection of hold-down lines.

24. In a balloon, meridian stress members attached to the junction of adjacent gores on the upper half of the envelope, a relatively stiff apex fabric interconnecting the upper ends of the meridian stress members, a catenary band secured around the envelope below the equator and having grommets in the lower catenary edge with free ends at intersections with the meridian lines of the gore junctions, means to secure the lower ends of meridian stress members with the band grommets and foot ropes whereby the entire lift strain is directly transmitted to the plurality of foot ropes.

25. In a balloon, an envelope having an apex cone, a plurality of gores, meridian

stress members running from the cone to the equator secured to the gore seams and comprising material of progressively increasing strength from the top down, and terminating at the lower ends in means for attachment of foot ropes.

26. In a balloon, an envelope having an apex convex cone, and an interior line secured to the underside of the cone away from its center and extending out of the bottom of the envelope to a point adjacent to the passenger compartment.

27. In a balloon, an envelope having a relatively stiff shedding-area surrounding the apex, a rope extending from adjacent the passenger compartment through the bottom of the envelope and through the interior to a crow's-foot attachment to the relatively stiff area around the apex and secured thereto at points remote from its central high point.

28. In a balloon, an envelope, a relatively stiff convex apex section, a crow's-foot attached to the underside of the stiff section remote from its center and merging in a control line extending through the balloon and out of the bottom to a point accessible to occupants.

29. In a balloon, a snow-shedding top section, comprising a convex area at the apex of material stiffer than the surrounding or adjacent envelope; means operable by the occupant to cause a depression of a considerable surface of said shedding top section at one time, and to permit its quick return to normal inflated position, whereby any snow or like accumulation will be jarred and caused to slide down the sloping sides.

30. In a spherical balloon, an envelope, an apex cone and a snow line comprising a control rope extending from the basket through the envelope and secured by a crow's-foot to the interior of the cone around its apex and having an extensible section in the line below the crow's-foot.

31. In combination in a balloon, an envelope and an appendix, of a relatively light sleeve secured to the inner walls of the appendix, substantially as described.

32. In combination in a balloon, an envelope and an appendix, of a relatively light sleeve secured to the inner walls of the appendix, and an automatic closing device to contract the appendix sleeve.

33. In a balloon, an envelope having the upper half of single-ply bleached fabric with the bare fabric surface outside and with white rubber backing on the inner surface.

In testimony whereof, I have signed my name to this application this 14th day of May 1923.

RALPH H. UPSON.
